(57) **CLAIM**

The ornamental design for a sofa component set, as shown and described.

DESCRIPTION

FIG. 1 is a perspective view of a first component of a sofa component set shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of a second component of a sofa component set shown separately for ease of illustration; FIG. 10 is another perspective view thereof; FIG. 11 is a front elevational view thereof; FIG. 12 is a rear elevational view thereof; FIG. 13 is a left side elevational view thereof; FIG. 14 is a right side elevational view thereof; FIG. 15 is a top plan view thereof; FIG. 16 is a bottom plan view thereof; FIG. 17 is a perspective view of a third component of a sofa component set shown separately for ease of illustration; FIG. 18 is another perspective view thereof; FIG. 19 is a front elevational view thereof; FIG. 20 is a rear elevational view thereof; FIG. 21 is a left side elevational view thereof; FIG. 22 is a right side elevational view thereof; FIG. 23 is a top plan view thereof; FIG. 24 is a bottom plan view thereof; FIG. 25 is a perspective view of a fourth component of a sofa component set shown separately for ease of illustration; FIG. 26 is another perspective view thereof; FIG. 27 is a front elevational view thereof; FIG. 28 is a rear elevational view thereof; FIG. 29 is a left side elevational view thereof; FIG. 30 is a right side elevational view thereof;

(Continued)

FIG. 31 is a top plan view thereof;
 FIG. 32 is a bottom plan view thereof;
 FIG. 33 is a perspective view of a fifth component of a sofa component set shown separately for ease of illustration;
 FIG. 34 is another perspective view thereof;
 FIG. 35 is a front elevational view thereof;
 FIG. 36 is a rear elevational view thereof;
 FIG. 37 is a left side elevational view thereof;
 FIG. 38 is a right side elevational view thereof;
 FIG. 39 is a top plan view thereof;
 FIG. 40 is a bottom plan view thereof;
 FIG. 41 is a perspective view of a sixth component of a sofa component set shown separately for ease of illustration;
 FIG. 42 is another perspective view thereof;
 FIG. 43 is a front elevational view thereof;
 FIG. 44 is a rear elevational view thereof;
 FIG. 45 is a left side elevational view thereof;
 FIG. 46 is a right side elevational view thereof;
 FIG. 47 is a top plan view thereof;
 FIG. 48 is a bottom plan view thereof;
 FIG. 49 is a perspective view of a seventh component of the sofa shown separately for ease of illustration;
 FIG. 50 is another perspective view thereof;
 FIG. 51 is a front elevational view thereof;
 FIG. 52 is a rear elevational view thereof;
 FIG. 53 is a left side elevational view thereof;
 FIG. 54 is a right side elevational view thereof;
 FIG. 55 is a top plan view thereof;
 FIG. 56 is a bottom plan view thereof;
 FIG. 57 is a perspective view of a eighth component of the sofa shown separately for ease of illustration;
 FIG. 58 is another perspective view thereof;
 FIG. 59 is a front elevational view thereof;
 FIG. 60 is a rear elevational view thereof;
 FIG. 61 is a left side elevational view thereof;
 FIG. 62 is a right side elevational view thereof;
 FIG. 63 is a top plan view thereof;
 FIG. 64 is a bottom plan view thereof;
 FIG. 65 is a perspective view of the second component, the fourth components, the fifth component, the sixth component, and the eighth component where the second component, the fourth components, the fifth component, the sixth component, and the eighth component are assembled together;
 FIG. 66 is a perspective view of the second component, the fourth component, the fifth component, the sixth component, and the eighth component where the second component, the

fourth component, the fifth component, the sixth component, and the eighth component are assembled together;
 FIG. 67 is a perspective view of the fourth component, the sixth component, and the seventh component where the fourth component, the sixth component, and the seventh component are assembled together; and,
 FIG. 68 is a perspective view of the first component, the second component, the third component, the fifth component, and the eighth component where the first component, the second component, the third component, the fifth component, and the eighth component are assembled together. The dash-dash broken lines in the drawings depict portions of the sofa component set that form no part of the claimed design.
